[57] **CLAIM**

The ornamental design for a combined switch and face plate or similar article, substantially as shown and described.

DESCRIPTION

FIG. 1 is a front, left perspective view of the combined switch and face plate or similar article showing my new design, the handle being in the upright position;
FIG. 2 is a front elevational view thereof, the handle being in the horizontal position;
FIG. 3 is a top plan view thereof;
FIG. 4 is a bottom plan view thereof;
FIG. 5 is a side elevational view taken from the right of FIG. 2;
FIG. 6 is a side elevational view taken from the left of FIG. 2.
